B. Hinkley,

Bed Bottom,

No 24,873.

Patented July 26, 1859.

UNITED STATES PATENT OFFICE.

BENJAMIN HINKLEY, OF TROY, NEW YORK.

BEDSTEAD.

Specification of Letters Patent No. 24,873, dated July 26, 1859.

To all whom it may concern:

Be it known that I, BENJAMIN HINKLEY, of the city of Troy, in the county of Rensselaer and State of New York, have invented

5 a certain new and useful improvement in that common kind of bedstead in which the side rails are held to the end rails and posts by means of tension-cords or rods which support the bed-bottom; and I do hereby 10 declare that the following is a full and exact description of the same, reference being had to the annexed drawings, making a part of this specification, in which—

Figure 1 is an isometrical projection, Fig. 15 2 a vertical longitudinal section, and Figs. 3, 4, 5, 6, 7 and 8, isometrical projections of parts, of one of my improved bedsteads.

The same letters refer to like parts in all the figures.

20 My invention consists in uniting the end-rails to the posts, in bedsteads of the kind first above mentioned, by means of dove-tailed tenons, *m* or *m'*, on the end-rails, and corresponding dove-tailed mortises, *n* or *n'*, 25 in the posts, the narrow side of the tenons being arranged even with the inner faces of the end-rails, and the corresponding narrow sides of the mortises being open, and on those sides of the posts which the ends 30 of the side-rails, *J*, *J*, bear against; so that when the tenons of the end-rails are inserted in the mortises, the narrow sides of the tenons will be even or nearly so with the face of the posts, so that the ends of the side- 35 rails will bear against the tenons of the end-rails, as shown in the annexed drawings; the tenons being either glued fast in the mortises, or left free to be removed therefrom, as circumstances shall require. I thus 40 unite together the end-rails and posts, of this kind of bedstead, by the dove-tailed tenons and mortises arranged as above described, in order that the end-rails shall thereby, not only hold the posts securely by 45 a cheap, neat, and tight joint, and shall also retain the requisite strength to withstand all the powerful strain which may be put upon them by the tension rods, but shall also at the same time, and by reason of the same 50 arrangement of the dove-tailed tenons and mortises, receive the pressure of the side-

rails, without the intervention of the posts; whereby the latter are left without any strain upon them tending to loosen them from the end-rails.

55

In bedsteads which have the posts framed to the end-rails by the common square or rectangular tenons and mortises, the end-rails are too liable to become split off at the shoulders of the tenons by straining the bed-supporting tension-rods, *a*, *a*, secured to the end-rails. To remedy that defect I first united the side and end rails into a frame entirely independent of the posts, as claimed in my U. S. Patent of Dec. 25, 1849; but in 60 that case it was necessary to make each post in two parts, with one part below and the other above the rails, which construction left the posts too weak, and the ends of the rails exposed, and increased the cost of the 65 bedstead. But by securing the posts by means of the dove-tailed tenons and mortises arranged as shown in the annexed drawings, I not only retain the strength of the end-rails so that they cannot be split or 70 broken by the tension of the rods, *a*, *a*, upon them; and also cause the end-rails to receive the pressure of the ends of the side-rails without the intervention of, or any strain 75 upon, the posts; but also make each post, *K*, 80 in a single piece extending from the floor to above the rails, and thereby cover up the bad-appearing ends of the rails at the same time that the bedstead-frame costs less than any other known to me of equal or sufficient 85 strength.

I am aware that it is not new to frame boards or timbers together by dovetailed tenons and mortises so arranged that the narrow side of the tenon is even with one 90 face of the part upon which it is made, and so that the narrow sides of the mortises are open, an example being shown in the common square wooden boxes formed of boards dovetailed together at their upright angles. 95 But I am not aware that in a bedstead-frame or any like structure having side-rails, end-rails, and posts arranged and held together by tension rods acting upon the end-rails, the posts and end-rails have been 100 framed together by dove-tailed tenons and mortises arranged in the particular manner

shown in the annexed drawings, or so as to secure the advantages, or for the purposes, above specified.

What I claim as new, and of my invention, and desire to secure by Letters Patent is—

The arrangement of the dovetailed tenons, m or m' , on the end-rails, B, and corre-

sponding dove-tailed mortises, n or n' , in the full posts, K, with the side-rails, J, and longitudinal tension-rods, α , as and for the purposes herein set forth. 10

BENJA. HINKLEY.
